UNITED STATES PATENT OFFICE.

CHARLES EMERY WOOD, OF GAS, KANSAS.

OPERATING-TABLE.

No. 907,432.

Specification of Letters Patent.

Patented Dec. 22, 1908.

Application filed March 27, 1908. Serial No. 423,663.

To all whom it may concern:

Be it known that I, CHARLES EMERY WOOD, a citizen of the United States, residing at Gas, in the county of Allen and State of Kansas, have invented a new and useful Operating-Table, of which the following is a specification.

The principal object of the present invention is to provide an operating table, particularly useful for emergency cases, inasmuch as it is constructed so that it is compactly foldable and very light in weight in order that it may be readily transported, the table furthermore being such that certain of the parts co-operate to perform a plurality of functions, thus greatly simplifying the structure.

The preferred form of construction is illustrated in the accompanying drawings, wherein:

20 Figure 1 is a perspective view of the table when extended and in position for use. Fig. 2 is a similar view showing the table folded for transportation. Fig. 3 is a longitudinal sectional view through the table when extended. Fig. 4 is a horizontal sectional view when contracted. Fig. 5 is a cross sectional view on the line 5—5 of Fig. 4.

Similar reference numerals designate corresponding parts in all the figures of the 30 drawings.

In the embodiment illustrated, an extensible body is provided, which consists of an inner section 6 and an outer section 7, these sections being slidably telescoped. The inner section comprises a top 8, a bottom 9 and side walls 10. The bottom 9, projecting beyond the side walls, produces flanges 11. The outer end of the section 6 carries a transverse shaft 12 supported in suitable brackets 13, 35 said shaft projecting beyond the sides of the table. Foot pieces 14 are mounted on the shaft between the brackets and a looped cord or cable 15, has its ends fastened to the shaft. A splint 16 may also be mounted on either 40 end of the shaft 12, said splint having a hooked end 17 that detachably engages with the shaft.

The top 8 of the inner section 6 is provided in its inner end with an opening 18, and slidably mounted in said section beneath the opening is a drawer 19, said drawer being movable through one of the side walls 10 and having a countersunk operating handle 20. A detachable receptacle 21 is placed in the 55 drawer, and constitutes in effect a bed pan that is located beneath the opening 18. An-

other drawer 22 is slidably mounted in the inner section 6, and also operates through one of the side walls 10, being provided with a suitable handle 23 that will lie flush with the outer face of the drawer. This drawer 22 is employed for instruments, bandages and other supplies.

The outer section 7 is slidable over the inner section and comprises a top 24, side 65 walls 25, and an end wall 26. The top 7 is slideable upon the top 8 of the inner section, and has its inner end concaved or cut away as shown at 27 so that when said outer section is in its outermost position, the opening 70 18 will be uncovered, but when the body is contracted or folded, said top 24 will constitute a cover for the opening 18 as will be evident by reference to Figs. 2 and 5. The side walls 25 slide upon the flanges 11 and are 75 movable over the side walls 10 of the inner section. When the outer section 7 is in its outermost position, the outer ends of the drawers 19 and 22 will be uncovered so that said drawers may be readily opened, but 80 when the said section is in its innermost position, one of the side walls 25 will completely cover the outer end of the drawer 19, and will also engage over a portion of the outer end of the drawer 22, as shown in Fig. 85 4, so that these drawers will be held in closed position by the outer section.

The two sections are held against detachment by retaining straps 28 which are fastened upon the outer section 7, extend transversely across the side walls 25 thereof and have undeturned lips 29 that slidably engage beneath the flanges 11 of the bottom of the inner section. A head-rest 30 is hinged, as shown at 31 to the outer end of the section 7, its upper face being preferably cushioned. Secured by a staple or other pivot 32 to the under side of the head-rest is a swinging bracket, in the form of a yoke 33. The side arms of said bracket or yoke are 100 connected at their lower ends by a cross bar 34. This bar is arranged to engage with any of the teeth 35 of a rack 36 fastened to the rear wall 26 of the outer body section. It will thus be evident that the head-rest may 105 be located at different elevations, or may be swung to a position upon the top 24 of the outer section, as illustrated in Fig. 2.

It will be evident, particularly by reference to Fig. 2, that when the device is contracted and folded, it occupies but comparatively little space, and can be readily trans-

ported so that it is particularly useful in emergency cases. When in use, the body is extended the desired distance by sliding the two sections outwardly, and said body can 5 be placed upon the ground, a bed, table or any other support of the proper height. When the body is extended, as shown in Fig. 1, the opening 18 is uncovered, and the contents of the drawers 19 and 22 are readily 10 accessible, inasmuch as said drawers can be opened. The shaft 12 constitutes a support for the foot pieces 14 and for the cable 15 employed in confinement cases, and in case of a broken limb, the splint or splints can be 15 detachably mounted on the projecting ends of the shaft 12, as illustrated in Fig. 1.

From the foregoing, it is thought that the construction, operation and many advantages of the herein described invention will 20 be apparent to those skilled in the art, without further description, and it will be understood that various changes in the size, shape, proportion and minor details of construction may be resorted to without departing from 25 the spirit or sacrificing any of the advantages of the invention.

Having thus fully described my invention, what I claim as new, and desire to secure by Letters Patent, is:—

30 1. In an operating table of the character set forth, an extensible body comprising slidably telescoped sections, a head - rest hinged to the end of one section and projecting beyond the same, a rack secured to 35 the end of the section beneath the head-rest and disposed in substantially vertical relation, and a supporting bracket pivoted to the head-rest and having a cross bar that detachably engages the different teeth of the 40 rack.

2. In an operating table of the character set forth, an extensible body comprising inner and outer slidably telescoping sections, and a receptacle movably mounted in the 45 inner section and removable therefrom when the outer section is in an outer position, said outer section when in its inner position extending over the receptacle and constituting means for retaining it in the inner section.

50 3. In an operating table of the character set forth, an extensible body comprising inner and outer slidably telescoping sections, and a drawer slidably mounted in the inner section and movable through one side thereof 55 when the outer section is in an outer position, said outer section when in an inner position extending over the outer end of the drawer and constituting means for retaining it in the inner section.

60 4. In an operating table of the character set forth, an extensible body comprising

slidably telescoped sections, the inner section being provided in its top with an opening disposed contiguous to the inner end that slides within the outer section, and the top 65 of the outer section being slideable over the opening and constituting a closure therefor, the central portion of the outer end of said top of the outer section being cut away to expose the opening when the outer section is 70 moved outwardly on the inner section.

5. In an operating table of the character set forth, an extensible body comprising slidably telescoped sections, one of which has an opening, and a removable receptacle 75 located in the body beneath the opening, the other section being movable over and constituting a cover for said opening and also being movable across and constituting means for retaining the receptacle in the 80 body.

6. In an operating table of the character set forth, an extensible body comprising inner and outer slidably telescoped sections, the inner section having on opening in its 85 top, a drawer slidably mounted in said inner section and movable through one side thereof, and a receptacle detachably mounted in the drawer, the top of the outer section being movable over the opening and one of the 90 side walls of said outer section being movable over the drawer to constitute the retaining means therefor when the sections are in their inner position.

7. In an operating table of the character 95 set forth, an extensible body comprising inner and outer slidably telescoped sections, a head-rest adjustably mounted on the outer end of one of the sections, a foot-piece mounted on the outer end of the other section, the inner section having an opening in its top and the top of the outer section being cut away to expose the opening and being movable over said opening, constituting a closure therefor, drawers slidably mounted in 100 the inner section and movable outwardly through the side thereof, one of the drawers being located beneath the opening, and a detachable receptacle mounted in said drawer, the corresponding side of the outer 110 section being movable over the drawers to hold them in closed condition when the opening is covered and the body is contracted.

In testimony, that I claim the foregoing 115 as my own, I have hereto affixed my signature in the presence of two witnesses.

CHARLES EMERY WOOD.
